ASH AND CIGARETTE BUTT RECEIVER

Valdis M. Pyatt, Great Falls, Mont.

Application August 18, 1936, Serial No. 96,691

4 Claims. (Cl. 206—41)

This invention relates to ash receptacles and particularly to a receptacle designed for taking care of and receiving ashes and the butts of cigarettes.

5 One of the objects of this invention is to provide means of this character which will permit ashes and the butts of cigarettes to be carried in a safe and sanitary way and which will prevent any chance of fires being started in the 10 woods, at home and under like circumstances by carelessly thrown down lighted cigarette butts.

Another object is to provide a device of this 15 character which is adapted to be carried in the pocket or clipped to the pocket and which includes an elongated receiving section and an upper section detachably connecting to the receiving section and having a cap, this upper section supporting an ejecting disk normally disposed in the lower end of the receiving section 20 which, when pulled out by detaching the upper section from the receiving section, withdraws with it the ashes, cigarette butts, etc., so as to clean the receptacle.

A further object is to provide means carried 25 by the upper section whereby ashes on a cigarette may be knocked off without knocking off the lighted end of the cigarette, or whereby a cigarette may be put out entirely before dropping it into the receptacle.

30 My invention is illustrated in the accompanying drawing wherein:—

Figure 1 is an elevation of an ash and butt receiver constructed in accordance with my invention;

35 Figure 2 is a vertical sectional view on an enlarged scale of the structure shown in Figure 1;

Figure 3 is a section on the line 3—3 of Figure 2;

40 Figure 4 is a section on the line 4—4 of Figure 2;

Figure 5 is a front elevation of the sleeve shown in Figure 2 but slightly modified therefrom.

Referring to this drawing which shows the 45 preferred form of my device, 10 designates an elongated metallic receptacle open at its upper end and closed at its lower end. The upper end of this receptacle is shown as being provided with opposed bayonet slots 11, though I do not 50 wish to be limited to this. Adapted to be disposed upon the upper end of this receptacle 10 is a cylindrical section or collar 12 which is reduced in diameter at its lower end, as at 13, this 55 reduced portion 13 fitting within the upper end of the receptacle 10 and being provided with op-

posed pins 14 which engage within the bayonet slots 11 so that upon a rotation in one direction, after insertion, the collar or section 12 will be locked upon the upper end of the section 10, and upon a rotation in the opposite direction and a 5 withdrawal of the section 12, the section 12 may be detached from the section 10.

The collar has attached to it the two longitudinally extending rods or strips 15 which carry at their lower ends the disk-shaped ejector 16, 10 which fits within the lower end of the barrel 10. Pivotal mounted upon the collar 12 is a cap 17, a spring 18 acting to retract this cap to an open position. The upper end of the collar 12 is reduced in diameter, as at 19, and the cap fits 15 over this reduced portion.

The collar is provided with the spring projected latch 20 and a knob or button 21 is provided which, when pushed inward, releases this latch from engagement with the cap 17, the cap being 20 provided with a recess or keeper for engagement with the latch when the cap is closed.

Preferably, though I do not wish to be limited to this, there is inserted within the collar a transversely arcuate sleeve 22 of thin metal, the 25 upper edge of which is cut so as to curve upwardly toward the middle of the sleeve and then downwardly toward the other edge of the sleeve. This sleeve is inserted within the collar 12 and, of course, does not project so high as to prevent 30 the closing of the cap. This sleeve is for the purpose of easily knocking off the ashes on the end of a cigarette, the sleeve being disposed with its center approximately opposite the hinged joint of the cap. While I do not wish to be 35 limited to this, there may be provided a convoluted wire 23 on the inner face of the sleeve forming a roughened surface against which the lighted end of a cigarette may be pressed and ground so as to put out the cigarette, this action causing the fire to drop down into the receptacle or barrel 10.

In the use of this device, the collar 12 is, of course, interlocked with the barrel or receptacle 10 and normally the cap is closed. Preferably, 45 though I do not wish to be limited to this, the barrel 10 is provided with a spring clip 24 whereby it may be supported within a pocket as fountain pens are supported. Ashes may be knocked off the cigarette and will drop down 50 into the barrel 10 and onto the ejector 16. The lighted butt of a cigarette may be also dropped down into this receptacle 10 and when the cap is closed, this butt will go out for lack of air, or the lighted end of the butt may be forced 55

against the convoluted wire 23 and ground away before the butt is dropped into the receptacle, or the butt, after the lighted end has been ground off, may be thrown aside without danger. The cap, as before stated, is normally closed, but as soon as the button 21 is pushed inward, the cap will spring open.

Obviously, the device might be made in a number of sizes, and obviously the ejector 16 might be supported by only one strip or rod 15 instead of the two shown.

Various modifications might be made in the minor details without departing from the spirit of the invention as defined in the appended claims.

What is claimed is:—

1. An ash and butt receptacle including an elongated tubular body closed at its bottom and open at its top, a cap operatively detachably engaging said receptacle to close it, and a sleeve disposed in the upper portion of said receptacle, the sleeve being arcuate in cross section and having a curved upper end extending beyond the upper end of the receptacle, the inner face of said sleeve being roughened to provide a surface against which the lighted end of a cigarette may be ground.

2. An ash and butt receptacle including an elongated tubular body closed at its bottom and open at its top, a cap operatively hinged to said receptacle to close it, and a sleeve disposed in the upper portion of said receptacle, the sleeve being arcuate in cross section and having a curved upper end extending beyond the upper end of the receptacle, the inner face of said sleeve hav-

ing a convoluted wire attached thereto against which the lighted end of a cigarette may be ground.

3. An ash and butt receptacle adapted to be carried in the pocket, including an elongated tubular body closed at its bottom and open at its top and having bayonet slots in its upper end, a tubular section having an outside diameter equal to the outside diameter of the body and having one end reduced to fit within the upper end of the body, said section having pins engageable in said bayonet slots, the tubular section having a supporting element extending downwardly into the lower end of the body and supporting an ejector at its lower end, and a cap hinged to the tubular section and adapted to close the same, a spring urging the cap to an open position, and a latch holding the cap closed.

4. An ash and butt receptacle adapted to be carried in the pocket, including an elongated tubular body closed at its bottom and open at its top, an elongated tubular section having one end formed and constructed to be inserted and tightly fit within the upper end of said tubular body, the tubular section having a supporting element extending downward into the lower end of the body and supporting an ejector at its lower end, the ejector and tubular section being unitarily insertable or removable into or from the tubular body, a cap hinged to the upper end of the tubular section and adapted to close the same, a spring urging the cap to an open position, and a latch holding the cap closed.
